DROP-LEAF TABLE

Merlin G. Pierson, Gatzke, Minn.

Application August 12, 1954, Serial No. 449,362

5 Claims. (Cl. 311—62)

This invention relates in general to furniture, and refers more particularly to a novel construction for drop leaf tables and similar articles.

It is a primary object of my invention to provide a table having an attached drop leaf which, when raised to its up or level disposition wherein it forms a continuation of the top, causes an auxiliary leg to move outwardly with respect to the central support and under the leaf to provide means for resisting tipping of the table when the drop leaf is loaded. In this connection, an important feature of my invention resides in the manner of connection of the leg with the central pedestal of the table so that movement of the leg is restricted to pivotal movement about a fixed axis. By providing for simple rotation of the leg, the member of moving parts is reduced to a minimum and there is substantially less wear and tear on the bearing surfaces than in more complex structures known to the art.

Another object of the invention is to provide a drop leaf table of the character described in which the means tying the leg and leaf together for simultaneous motion also serves as a brace for the leaf in its up position. According to the invention, the leaf and leg are so tied together by the brace means that retraction of both the leg and the brace takes place when the leaf is folded. A feature of the invention in this respect resides in the manner of construction of the brace and the fashion in which it is connected with the respective elements.

A further object of the invention is to provide a drop leaf table of the character described in which the stationary central pedestal of the table provides a housing for the leg and drop leaf bracing structure when the drop leaf is down and the leg in a retracted position. As a result, the leg and brace mechanism are concealed from view thus preserving a pleasing appearance.

Still another object of the invention is to provide a drop leaf construction which is readily adaptable to both solid and expandable top tables.

Another object is to provide a drop leaf and extension leg arrangement for tables in which the auxiliary leg, when in its extended position, operates to prevent tipping of the table and yet is so disposed with respect to the edge of the table as to permit those using the table to sit up to the edge with a minimum of interference with the legs and feet.

A further object is to provide a novel latching mechanism for the drop leaf and auxiliary leg which can be released with ease, and yet which permits the table to be moved about freely without danger of collapse. In this connection, it is a further object to provide a latching mechanism which is self-engaging upon movement of the leaf to the up position.

Other and further objects, together with the features of novelty appurtenant thereto, will appear in the course of the following description.

In the accompanying drawing, which forms a part of and is to be read in conjunction with the accompanying

2

specification, and in which like reference numerals indicate like parts in the various views:

Fig. 1 is a side elevation of a table embodying my invention showing one leaf in the down position and one leaf in the up position, parts being in section and parts broken away for purposes of illustration;

Fig. 2 is an end elevation showing the leaf in the up position;

Fig. 3 is a perspective view from inside the pedestal showing the details of the latching mechanism, parts being broken away to indicate length; and

Fig. 4 is a plan view of the underside of the leaf in the area of the latch release trip mechanism.

Referring to the drawing, and particularly to Figs. 1 and 2, reference numeral 10 indicates generally a flat rectangular table top which is supported substantially at its center by an upright pedestal structure comprising two hollow rectangular members 12. In the illustrated embodiment, the top is carried on a rail structure 13 supported on the upper end of the pedestal members 12. Diagonal legs 14 are secured to the opposite sides of the pedestal sections 12.

Pivoted connected with the edge of the rail structure 13 about axes 15 on opposing edges of the table are drop leaves 16. Preferably each leaf 16 is equal in width with the width of the table top 10, and each is capable of being swung from a horizontal position in which it forms an extension of the top to a vertical position adjacent its respective pedestal 12.

To support each leaf 16 in its up or horizontal position, there is provided a diagonal brace element generally indicated at 17 which is pivoted at one end to the underside of the leaf 16 and at the other end to the top of an extension leg 19. As is best seen in Figs. 2 and 3, the brace 17 is preferably formed of two spaced parallel members 20. The upper ends of these members are pivotally connected with the drop leaf 16 through vertically disposed flange members 21 which are secured to the underside of the leaf and spaced equally with the brace members 20. Hinge straps 22 and 23 are secured respectively to the flanges 21 and brace members 20, and hinge pins 24 secure the two together in pivotal relationship.

The manner of connection of the brace members 20 at their lower ends with the extension leg 19 is best seen in Figs. 1 and 3. The leg 19 is backed on its inner end with a metal plate 25 affixed to the leg by means of screws 26. The upper end of the plate 25 has formed thereon a sleeve 25a through which extends a pintle 26. Straps 27 are secured to the upper edges of the respective brace members 20, and these straps have their extending ends curled to form sleeves 27a which fit over and are preferably keyed to the pintle 26. The brace members 20 are spaced from one another a distance sufficient to permit the leg 19 to pass therebetween upon relative movement of the leg and brace members with respect to the pintle 26.

The metal plate 25 also provides, in the illustrated embodiment, the means by which the leg 19 is pivotally connected with its pedestal member 12. As shown in Figs. 1 and 2, the inner end of the leg 19 is positioned in an aperture in the face of the pedestal member 12 having vertical edges 28 and a bottom edge 29. A hinge strap 30 (also see Fig. 3) is secured to the inside wall of the member 12 adjacent the bottom edge 29 of the opening. The strap 30 is provided with spaced pin receiving lugs 30a, and disposed between the lugs 30a is a sleeve 25b formed at the lower edge of the plate 25. A pintle 31 passes through the lugs 30a and sleeve 25b to form the hinge connection of the leg 19 with the table.

It will be noted that located above the aperture in which leg 19 is received, and forming an enlarged con-

tinuation thereof, is a second aperture having vertical parallel edges 32. This second aperture is slightly wider than the width of the brace element 17 (from outside edge to outside edge of the members 20), and terminates at its upper end adjacent the underside of the table top 10. As will be hereinafter described, the apertures in the member 12 provide the necessary entry and exit for the brace 17 and leg 19 into the hollow interior of the pedestal members 12.

From the description thus far, it will be understood that the leaf 16, brace 17 (comprising the spaced members 20), and leg 19 are so connected with one another that upon movement of the leaf from its up position to its down or depending vertical position, the respective parts assume the positions shown in the broken lines in Figs. 1. In the down position, the leaf is indicated at 16', the brace at 17' and the leg at 19'. As the leaf 16 descends about its pivot 15, the brace 17 exerts a counterclockwise turning moment on the leg 19, and the leg rotates about its axis 31. At the same time the brace 17 moves inwardly through the aperture in the pedestal member 12 defined by edges 32. It will be evident from the drawing that at one point in the movement, the tip of the retracting leg 19 passes between the brace members 20.

A novel feature of my invention resides in the means I have developed for locking the leaf 16 in the up or horizontal position. As shown in Fig. 3, secured to the plate 25 and thus to the leg 19 is a bar 33 pivoted about a central pin 34 for movement about an axis substantially normal to the plane of plate 25. The bar 33 is spaced away from the plate a distance sufficient to clear the sleeves 27a at the ends of the brace members 20 so that it is capable of unimpeded pivotal motion about pin 34. A curved leaf spring 35 engages the bar 33 on one side of pin 34, the other end of the spring bearing against a pin 36 affixed to plate 25, and a stop pin 37 is provided for engaging the underside of the bar on that side of pin 34 opposite from spring 35. As will be evident, the bar 33 is thus normally maintained in a substantially horizontal position by the spring 35, but is capable of being pivoted against the action of the spring in a counterclockwise direction.

As shown by the broken lines in Fig. 2, the ends of the bar 33 project laterally beyond the brace members 20. The ends bear inwardly against stops 38 and 39, respectively, which are formed as vertical projections on bracket members 40 and 41. The brackets 40 and 41 are rigidly secured to the opposite inside walls of the pedestal member 12 by screws 42, and are so spaced as to permit movement of the brace members 20 and legs 19 therebetween.

Referring particularly to Fig. 3, the stops 38 and 39 are formed as triangularly shaped vertical flanges. The left hand stop 38 is so located as to engage the upper half of its adjacent end of the bar 33, and conversely, stop 39 engages the lower half of the opposite end. This effectively prevents the downward pivoting of the leaf 16, the stops 38 and 39 serving as thrust members which act against the bar 33 to prevent rotation of the leg 19 to which the brace members 20 for the leaf are connected.

Release of the latch mechanism is accomplished by pivoting the bar 33 about its axis 34 in a counterclockwise direction until the upper edge of the bar at the left end clears the point of stop 38 and the lower edge at the right end is lifted above the point of the stop 39. Once the bar has been disengaged from the stops, the leg 19 is free to pivot inwardly about its axis 31, and the leaf can be lowered as has been hereinbefore described.

The disengagement of the bar 33 from the stops 38 and 39 is accomplished through a pull trip member 43 which is located on the underside of the leaf 16 near its outer edge. The trip member 43 is L-shaped in construction, having a flat portion 43a which is connected for sliding movement with a channel member 44 secured to the underside of the leaf, and has affixed thereto a pull

rod 45 extending inwardly toward the top 10 between the brace flange members 21. The inner end of the pull rod 45 (see Fig. 3) is pivotally connected with an L-shaped crank arm 46 adapted to rotate a shaft 47 which is supported on the underside of the rail structure 13 by journals 48. A second crank arm 49 is formed on the opposite end of shaft 47 from the L-shaped crank 46, and arm 49 is pivotally connected at its outer end with a vertically disposed push rod 50. The rod 50 extends downwardly adjacent the inside surface of the hollow pedestal member 12 and terminates in a bent portion 50a which is adapted to engage the upper edge of the left-hand end (as seen in Fig. 3) of the latching bar 33.

As is best seen in Figs. 1 and 2, the trip member 43 is provided with an auxiliary lock mechanism which prevents accidental tripping. This comprises a pivotal member 51 connected with the plate 43a of the trip member 43. The member 51 is generally L-shaped in construction and is pivotally hung between two spaced downwardly extending flanges 52 secured to the plate portion 43a of the trip member 43 and straddling the central elongated slot 43b. The member 51 is supported by a pivot pin 53 connected with the flanges 52, and its horizontally disposed leg is provided with an upwardly projecting detent 51a which engages a keeper recess 54 in the web of the channel 44 through the slot 43b to normally prevent relative sliding movement between the trip member 43 and the channel 44.

To release the trip member 43 and thus permit it to be pulled outwardly toward the edge of the table, the operator need only engage the vertical depending leg of the member 51 and pull outwardly. This disengages the detent 51a from the recess 54, and frees the trip member 43 for movement. Once clear of the recess 54, it will be evident that detent 51a will ride freely along the surface of the channel 44 until the trip member 43 is returned to its original position whence it again is forced by the gravity pull on the member 51 to advance into the recess.

The pulling of the trip member 43, once the auxiliary lock 51 has been disengaged, causes rod 45 to move outwardly thus turning crank arm 46 and with it shaft 47. This in turn causes the arm 49 to pivot downwardly and exert a downward thrust through push rod 50 on the end of the latching bar 33. This thrust causes the bar 33 to pivot a sufficient distance to disengage the bar from the stops 38 and 39, and the leaf 16 is free to drop to its down position.

Upon lifting of the leaf 16, the latch bar 33 re-engages with the stops 38 and 39 automatically. As the bar approaches the stops 38 and 39, the edges of the bar are engaged by the inclined surfaces on the stops. Further movement causes the bar to pivot against the action of the spring 36 until the ends of the stops are reached. Once past the ends of the stops, the bar 33 snaps back to its original horizontal position under the influence of spring 36, and the drop leaf 16 is again locked in its up position with the leg 19 extended.

It will be noted from Fig. 1 that the point of pivotal connection of the pull rod 45 with the crank arm 46 is located closely adjacent the pivot axis 15 for the drop leaf 16. This permits free swinging movement of the leaf without any binding in the latching mechanism.

From the foregoing it will be seen that this invention is one well adapted to attain all of the ends and objects hereinabove set forth together with other advantages which are obvious and which are inherent to the structure.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown

in the accompanying drawings is to be interpreted as illustrative and not in a limiting sense.

Having thus described my invention, I claim:

1. A drop leaf table comprising an upright pedestal, a horizontally disposed top mounted on said pedestal, a drop leaf pivotally connected with said top and movable from a horizontal position in which it forms an extension of the top to a dropped vertical position, an extension leg pivotally connected with said pedestal and having a first position extending outwardly from said pedestal beneath said leaf and a second position beneath said top, and linkage connecting said leaf with said leg to cause said leg to move from said first position to said second position upon movement of said leaf from its horizontal position to its dropped position and to cause said leg to move back to its first position upon lifting of the leaf back to its first position.

2. A drop leaf table as in claim 1 including means for releasably latching said leaf in its horizontal position.

3. A drop leaf table comprising an upright hollow pedestal having an aperture in one vertical side, a horizontal top mounted on said pedestal with one edge adjacent said one side, a drop leaf pivotally connected with said top for movement about a horizontal axis adjacent said one edge between a horizontal position wherein it forms a continuation of said top to a dropped vertical position below said axis and adjacent said one side, an

extension leg having its inner end pivotally connected with said pedestal for movement about a fixed axis substantially parallel with the pivot axis of the leaf and movable between a first position in which said leg extends outwardly from said pedestal beneath said leaf to a second position within said pedestal, said leg passing through said aperture upon movement from one position to the other, and brace means connecting said leaf with said leg at points remote from their respective pivot axes and tying said leaf and leg together for simultaneous movement from their respective horizontal and first positions to their dropped and second positions and back again, said aperture being formed to permit passage through said one side of said brace means.

15 4. A table as in claim 3 wherein said leaf in its dropped position covers said aperture.

5. A table as in claim 3 including means for releasably latching said leaf in its horizontal position.
